UNITED STATES PATENT OFFICE.

MICHAEL MURRAY, OF CHICAGO, ILLINOIS.

SAFETY APPLIANCE FOR ELECTRIC SWITCHES.

Application filed August 19, 1918. Serial No 250,442.

To all whom it may concern:

Be it known that I, MICHAEL MURRAY, a citizen of the United States, residing in Chicago, in the county of Cook and State of Illinois, have invented a new and useful Improvement in Safety Appliances for Electric Switches, of which the following is a specification.

This invention relates in general to safety appliances for electric switches, and more particularly to safety appliances provided in connection with switches in industrial plants using electric power, factories and other places using relatively high current, although it will be manifest that the invention may be used to advantage with switches in any circuits where it is desired to prevent manipulation of the switch under predetermined conditions.

In industrial plants and factories using electric power, it not infrequently happens that an operator or workman in making repairs or adjustments requires that the condition of the circuit be maintained. It may be that it is necessary that current be continually applied to a particular apparatus while the repairs or adjustments are being made or that the circuit be left open. Sometimes after a workman has arranged the switch in the position he desires and gone to the apparatus requiring his attention at some distance from the switch, another employee may inadvertently or maliciously change the arrangement of the switch notwithstanding the necessity of the previously arranged condition, with resulting injury to the apparatus or to the workman working upon it.

I am aware that in the past, arrangement has been made to lock the switch arm in either opened or closed position or both by the use of a padlock. This method of protecting the workman has been found ineffective for the reason that the padlocks being readily stolen or lost soon disappear and for the further reason that the ordinary employee or workman does not usually go to the trouble of first arranging the switch as he may desire it and then attaching the padlock.

A principal object of my present invention is the provision of a safety appliance for electric switches which may be readily arranged by a workman to maintain the switch in desired electrical condition and without requiring more than a mere open-

ing of a housing door or equivalent single action.

The construction and arrangements of the parts of an appliance in which my invention may be embodied is preferably such that after the establishment of such condition rearrangement of the device is impossible without a full realization of the fact that it has been previously arranged intentionally and probably for a specific purpose.

A further object of the invention is a provision of such an appliance, adapted by its construction to enforce a regulation to the effect that rearrangement can only be permitted after a report to and under the authorization of proper authority.

A still further object of the invention is a provision of a device of the character described, which will prevent a person manipulating a switch from being injured or burned by a flash caused by opening or closing the switch or by blowing of a fuse.

Another object of the invention is the provision of an appliance of the character described, which will be strong and durable in use and which may be cheaply manufactured and readily installed or substituted for the switch box already generally in use.

Numerous other objects and advantages of the invention will be apparent from the following description which, taken in connection with the accompanying drawing, illustrates a preferred embodiment thereof.

On the drawing,

Figure 1 is a horizontal section through an apparatus embodying my invention;

Fig. 2 is a front elevation of the same, the door being open as shown in section;

Fig. 3 is a section taken substantially on the line 3—3 of Fig. 1; and

Fig. 4 is a detail of certain parts.

For the purpose of illustrating my invention, I have shown on the drawing a conventional electric switch comprising the usual base 10, switch blades 11, operating handle 12 and feeding and delivery wire 13. The safety appliance in the form shown on the drawing comprises a metal switch box having side walls 14, rear wall 15, upon or through which the base 10 is secured, top and bottom walls 16, and the closure or door 17 spring-hinged along one edge 18 in the present instance.

It is intended that the switch shall only be operated when the door is in fully closed position and in order that it may be then

manipulated I provide a crank rod 19 having alined bearings 21 in the sides of the housing and having also an offset part 22 disposed within the housing. This part is connected by a yoke or strap 23 with the switch handle 12.

The portion of the rod 19, which extends outside the casing or housing, is bent up at 24 and may be provided with a handle 25. 10 Swinging of the handle will therefore produce opening and closing swinging movement of the switch blades. Means are provided to be projected across the path of movement of the handle of the switch except when the door is fully closed, and this means in the present instance consists of an obstruction formed of a metal plate 26 of box-like form, which is fastened upon a slide bar 27, mounted in bracket straps 28 15 fixed on the inside of the housing side walls. This bar is connected by a link 29 with a lug 31 on the door, so that as soon as the door starts to open link 29 pulls the slide bar 27 toward the left (viewing Fig. 1) from the position shown in dotted lines. When the door is fully opened the slide bar has moved the obstruction to the position shown in full lines.

A latching device is provided to lock the 30 slide bar against return movement after the door has been once fully opened. This device comprises in the present instance a latch lever 32, pivoted at 33 on the left hand bracket 28 and having a hooked end 34 35 adapted to engage in a slot or recess 35 provided near the end of the slide bar 27. A spring 36 pulls upwardly on the latch and holds it in engaged position. The latch lever 32 has a tail 37 positioned just above 40 a key hole 38 in the forward side of the bracket strap 28, so that release of the side bar to permit closing of the door and manipulating of the switch can only be accomplished through the use of a suitable 45 key. A casing plate 39 is preferably disposed over the forward face of the bracket and may if desired entirely encase the bracket.

It will be manifest from the foregoing 50 description that a workman, desiring to repair a line shaft or other piece of mechanism ordinarily driven by electricity, has only to open the switch and then open the door its full distance to lock the switch in 55 open position, cutting off the power to the desired apparatus, or if the adjustment or repairs require the continued presence of the current he may open the door to its full extent locking the switch in closed position. 60 It is intended that where safety appliances embodying my invention are used the key to the latch will be in the hands and only in the hands of some person of competent authority as for example the foreman or 65 shop superintendent so that further ma-

nipulation of the switch cannot be accomplished without his knowledge and consent. It will be noted that the door may be opened partly without causing the latch to operate, thereby permitting inspection of the 70 switch conditions.

Since the switch can only be moved when the door is closed, there is no danger of a flash, incidental to the closing or opening of the switch, burning an employee and in 75 view of the fact that the switch can only be manipulated when the door is closed there is little likelihood of the switch being left open except by deliberate intent for under such conditions the switch cannot be 80 shifted. The construction of the appliance therefore insures that the door be left closed unless it be deliberately left open.

It is thought that the invention and many 85 of its attendant advantages will be understood from the foregoing description, and it will be apparent that various changes may be made in the form, construction and arrangement of the parts without departing from the spirit and scope of the invention or sacrificing all of its material advantages, the form hereinbefore described 90 being merely a preferred embodiment thereof.

I claim:

1. A safety appliance for electric switches, 95 comprising a switch housing having a door closing a chamber containing a switch, and means operatively connected with the door, for preventing manipulation of the switch except when the door is in completely closed position, said means being adapted to be automatically locked in obstructing position when the door is moved to a predetermined point.

2. A safety appliance for electric switches comprising a housing, a door for closing same, a switch mechanism mounted within said housing, a movable member acting under the influence of the door for moving into the path of the switch arm, and means locking the parts in assumed relation when the door is moved to predetermined position, said means requiring unlocking by a key or other instrument 115 not attached to the apparatus.

3. A safety appliance for electric switches, 120 comprising a housing, an obstruction projectable into the path of the switch arm, and means automatically locking the door in a predetermined position with an obstruction across the path of movement of the switch arm.

4. A safety appliance for electric switches, 125 comprising a housing, a door in said housing, and an obstruction projectable upon opening movement of the door into the path of a switch arm within the housing and connected with the door, and means of latching the door in fully open position with the 130

obstruction across the path of the switch arm.

5. A safety appliance for electric switches, comprising a housing, a door in said housing, and an obstruction projectable upon opening movement of the door into the path of a switch arm within the housing and connected with the door, and means of latching the door in fully open position with 10 the obstruction across the path of the switch arm, said obstruction being moved by the door in its initial opening movement into operative position.

6. A safety appliance for electric switches 15 comprising a single chamber housing containing switch mechanism, a door for said housing, and means movable by the door for controlling manipulation of the switch and locking the door in open position, said means 20 requiring release thereafter by a separate key or implement unattached to the door or housing.

7. A safety appliance for electric switches comprising a housing having a door, means extending without the housing for manipulating the switch, means for rendering said switch manipulating means inoperative when the door of the housing is opened, and a key-controlled lock automatically operable to lock the door when it arrives at fully open position, thereby positively preventing operation of said switch manipulating means. 25 30

8. A safety appliance for electric switches, comprising a switch housing, a door closing said housing, means operable by the opening of the door to obstruct closing movement of the switch, and means automatically locking the door in a predetermined position with said obstructing means across the path of closing movement of the switch. 35

MICHAEL MURRAY.
